UNITED STATES PATENT OFFICE.

JAMES L. BROCKNEY AND CHARLES E. GEORGE, OF DETROIT, MICHIGAN.

SPARK PLUG.

Application filed April 6, 1922. Serial No. 550,057.

To all whom it may concern:

Be it known that we, JAMES L. BROCKNEY and CHARLES E. GEORGE, both citizens of the United States, residing at Detroit, in the county of Wayne and State of Michigan, have invented certain new and useful Improvements in Spark Plugs, of which the following is a specification.

This invention relates to spark plugs and has special reference to a spark plug with a movable electrode terminal.

In the construction of spark plugs it is well recognized that stationary electrode terminals soon have the sparking points coated with carbon deposits or otherwise deteriorated so that they no longer are effective for ignition purposes. It has been sought to overcome the objections to this type of spark plug by proving a movably supported electrode terminal such as a pendulum, loose ball or the like but these have not been found entirely satisfactory. It has also been sought to overcome the inherent deficiencies of spark plugs by the provision of an electrode terminal in the form of a small propeller which is caused to rotate by the gases flowing past it. This form has been found fairly good when new but is open to the very serious objection of having a tendency to stick or freeze and thus become, in effect, a stationary electrode.

The principal and most important object of the present invention is to provide an improved form of spark plug embodying the best feature of the propeller provided plugs but having in addition certain novel arrangements whereby the defects due to sticking and the like are overcome.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:—

Figure 1 is a longitudinal medium section through a spark plug constructed in accordance with this invention, the view being on a scale giving the plug device the length and breadth of the standard size commonly used in gasoline and other like engines.

Figure 2 is an end view showing the sparking terminals.

Figure 3 is a longitudinal section through the lower part of the central electrode sleeve.

Figure 4 is a section on the line 4—4 of Figure 3.

Figure 5 is a section on the line 5—5 of Figure 3.

In the embodiment of the invention herein disclosed the improvements have been shown in connection with a standard spark plug of well known make.

This spark plug has the usual shell 10 wherein is fitted a porcelain insulator 11 held securely in place by means of a nut 12. This insulator terminates well above the lower or spark gap end of the shell which is provided at this end with an enlarged chamber 14. The insulator is provided with the usual central opening 15 which terminates below in an enlarged portion 16 and through this opening 15 extends the central electrode which consists of a rod 17 provided, at the lower part just below the opening 15, with a collar 18 which bears against a suitable packing 19. The upper end of the electrode is threaded and projects above the insulator. On this threaded end is provided the washer 20 and nut 21, for holding the electrode rigidly in position, and the binding nut 22 for the wiring terminal. The parts just described are practically of ordinary and well known construction throughout.

It is to be noted that the rod 17 is continued below the collar 18 and on this lower end is mounted a long sleeve 23 which extends up into the opening 16 and is so proportioned with respect to the rod that it can revolve freely thereon without possibility of sticking, this arrangement being indicated in an exaggerated manner in the drawings by showing considerable clearance between these parts although, in actual construction, the necessary clearance is obtained by making the bore of the sleeve a few thousandths of an inch greater than the diameter of the rod and its length very slightly less than the distance between the collar 18 and a head 24 formed on the end of said rod to hold the sleeve in position. It is to be noted that the major portion of the sleeve lies in the opening 16 where it is protected from direct contact with flame or explosion, and is thus kept from heating too greatly. Also the rod 17 is protected so that it is kept relatively cool. Due to these features "freezing" of the

sleeve on the rod is practically impossible. At the lower end of the sleeve is a peripheral groove 25 wherein is fitted the hub of a propeller 26, this hub also having proper clearance to permit free revolution on the sleeve. These parts are assembled by forming the sleeve with a reduced end, slipping the propeller in place and beading over the end of the sleeve to form the groove. Due 10 to this construction, the sleeve being kept relatively cool, there is practically no tendency of the propeller to "freeze" on the sleeve. Thus, owing to the double precaution taken, it is found in practice that the propeller 15 never refuses to function by revolving in the end of the shell at each explosion.

It is obvious that the ends of the propeller blades are so spaced from the shell that the proper spark gap is obtained.

20 There has thus been provided a simple and efficient device of the kind described and for the purposes specified.

Having thus described the invention, what is claimed as new, is:—

25 1. In a spark plug, a shell forming the outer electrode, a central electrode within

the shell and insulated therefrom, a sleeve revolvably mounted on the lower end of the central electrode, and a propeller mounted on said sleeve, said propeller being freely 30 revolvable with respect to the sleeve and having its blade ends spaced from the shell to form spark gaps.

2. In a spark plug, a shell forming an outer electrode an insulator within said shell and having an opening therethrough terminating in an enlarged portion at its lower end, a rod passing through said opening and forming a central electrode, a sleeve revolvble on said rod and having its major portion located in the enlarged portion of the opening whereby to keep the sleeve relatively cool, and a propeller at the lower end of the sleeve within said shell and having blade 40 ends spaced from the wall of the shell to 45 form spark gaps, said propeller being freely revolvble on the sleeve.

In testimony whereof we affix our signatures.

JAMES L. BROCKNEY.
CHARLES E. GEORGE.
